UNITED STATES PATENT OFFICE.

PAUL A. BANCEL, OF NUTLEY, NEW JERSEY, ASSIGNOR TO INGERSOLL-RAND COMPANY, OF JERSEY CITY, NEW JERSEY, A CORPORATION OF NEW JERSEY.

CONDENSING UNIT.

Application filed April 10, 1923. Serial No. 631,106.

To all whom it may concern:

Be it known that I, PAUL A. BANCEL, a citizen of the United States, a resident of Nutley, county of Essex, and State of New Jersey, have invented a certain Condensing Unit, of which the following is a specification accompanied by drawings.

This invention relates to condensers, but more particularly to a condensing unit comprising a surface condenser and a cooler connected thereto and forming a part of the unit.

The objects of the invention are to simplify the construction and reduce the cost of manufacture of condensing units having a cooler and devaporizer, in which the latter part of the total heat abstraction takes place. Another object of the invention is to produce a unitary construction which is compact and occupies substantially the minimum of space, with less number of parts than heretofore, and simplified piping.

The invention is shown in one of its preferred forms in the accompanying drawings, in which—

Figure 1 is a side elevation of a condensing unit.

Figure 2 is an end elevation partly in transverse section.

Figure 3 is a longitudinal sectional elevation through the cooler of Figure 2 on the line 3—3, looking in the direction of the arrows.

Figure 4 is a detail transverse sectional top plan view of a portion of the cooler on the line 4—4 of Figure 3 and also on the line 4—4 of Figure 5 looking in the direction of the arrows, and

Figure 5 is a detail transverse sectional elevation on the line 5—5 of Figure 3, looking in the direction of the arrows.

Referring to the drawings, the condenser A shown in Figure 1 and partly broken away and in section in Figure 2, may be of any suitable form, and is preferably a surface condenser, provided with cooling elements in the form of the usual cooling tubes A'. The condenser A may be of wedge shaped form, as shown, that is, larger at

the top and smaller at the bottom, and the mixture of condensable vapor and gas, as steam and air, is admitted to the top and after passing downwardly over the condensing surfaces, passes out of the bottom through the outlet B.

The present invention relates to the entire condensing unit, which includes a cooler C, or that portion of the condensing unit in which the latter part of the total heat abstraction takes place. The cooler C, in this instance, in the form of an augmenter cooler, substantially like that shown in my U. S. Patent No. 1,506,805, granted September 2, 1924, for augmenter cooler, is adapted to be incorporated with the condenser A, and is preferably arranged with one side against the lower portion of one side of the condenser, as shown particularly in Figure 2, at an angle to the vertical axis of the condenser, owing to the general shape of the condenser shell. The cooler C is preferably of wedge shaped or pyramidal form, that is, larger at the bottom and smaller at the top, although not necessarily of this form, and the mixture of air and vapor coming from the condenser after the major portion of steam has been condensed, passes upwardly through the cooler, which is provided with multiple cooling elements or surfaces. A suitable evacuator, as a vacuum pump, may be connected to the cooler at the outlet D preferably at one end of the casing. The function of the cooler, as well understood, is to complete the condensation of the vapor as the mixture flows from the surface condenser, and in accordance with my present construction, the cooler preferably includes a devaporizer formed by the chamber E and associated parts, and an intercooler comprising the chamber F forming a part of the cooling apparatus. The devaporizing chamber E and the intercooler chamber F are in communication at the top of the cooler, as indicated particularly in Figure 3, and a plain cover G is shown in the present instance, over the top of the cooler at the location at which one or more augmenter ejectors of the jet type could be used to discharge into the intercooler F and to increase the absolute pressure of air in the intercooler, as shown in my aforesaid patent and therein claimed.

The cooling apparatus C as a whole, is adapted to be removably secured against the flange H on the side of the condenser A, as by means of the bolts J and the space K between the wall of the condenser shell, and the inner wall or tube sheet L of the cooler forms a water chamber or compartment for the circulation of cooling water

through the cooling elements of the cooler. The cooler is provided with an outer head O forming a water circulation compartment P between the head and the outer tube sheet Q of the cooler. The casing of the cooler forms an inlet chamber R at the bottom connecting with the space S at the lower portion of the condenser, so that the condensate may be withdrawn through the common outlet T between the condenser and the cooler.

I am not to be understood as limiting the invention, except as defined in the claims, to any particular condenser or any particular cooler comprising a devaporizer and an intercooler, but for purposes of illustration I have shown a devaporizer and intercooler provided with cooling elements in the form of hollow cores or grids U, mounted transversely in rows in the cooler, communicating with the water space K and the water head O of the cooler. These grids may be like those described in my Patent No. 1,380,460, granted June 7th, 1921, for method and apparatus for devaporizing and cooling. The grids U may be mounted in the tube sheets in the cooler in any suitable manner, as by means of nipples V, and hand holes W are preferably provided for the cooler opposite each grid. The grids U are preferably closer together in the top rows than in the bottom rows, which decreases the width of the streams of flowing mixture, the greater the relative amount of air in the mixture.

As described in my said Patent No. 1,380,460, interference of air in the mixture with the process of condensation from the flowing stream can be largely eliminated by the proper disposition of skin resistance in the path of the flow, and I retard the flow of the mixture at points between the relatively cold condensing surfaces X of the grids, but remote from the surfaces themselves. In order to retard the flow of the steam and air at points between the surfaces X of the grids U, but remote from said surfaces, I have shown transverse fins or flanges Y formed on the grids U and lying in intermeshing relation in planes substantially normal to the core surfaces X. These fins or flanges Y interpose numerous skin friction surfaces between the cooling surfaces and retard the flow in planes normal to said surfaces. At the condensing surfaces proper, indicated at X, the skin resistance remains the same as before, and as though the flanges Y were absent.

The cooling water for the devaporizer and for the cooler, is supplied through the common inlet a and through the inlet pipe a' to the water head O, through which the water is guided by the baffle a², and after passing through the grids of both the devaporizer and intercooler, is discharged at the common outlet b from the water space or compart-

ment K. This construction does away with extra piping to and from the intercooler and forms a cheaper and more compact construction than heretofore. The water enters at the water inlet a and is assumed to pass in any suitable manner to and through the main condenser A and is discharged at the discharge outlet c, so that the elements of the entire unit are supplied from a common water inlet a. The opening d is an atmospheric relief or exhaust opening for use as desired.

I claim:

1. A condensing unit comprising a surface condenser having condensing elements and a shell larger at the top and smaller at the bottom with a vapor inlet at the top and an outlet at the bottom, and a cooler having devaporizing and cooling elements and a casing larger at the bottom and smaller at the top with a vapor inlet at the bottom and an outlet at one end, one side of the cooler casing being removably connected against the side of the condenser shell with provision for a water space between the condenser and cooler, and connections for passing water through the condensing elements of the condenser, and through the cooling and devaporizing elements of the cooler.

2. A condensing unit comprising a surface condenser having condensing elements and a shell larger at the top and smaller at the bottom with a vapor inlet at the top and an outlet at the bottom, and a cooler having devaporizing and cooling elements and a casing larger at the bottom and smaller at the top with a vapor inlet at the bottom and an outlet at one end, one side of the cooler casing being removably connected against the side of the condenser shell with provision for a water space between the condenser and cooler, a common water inlet for the complete condensing unit, water outlet connections for the condenser and cooler, and connections whereby water is passed through the condensing elements of the condenser and through the cooling and devaporizing elements of the cooler.

3. A condenser unit comprising a surface condenser having condensing elements and a shell larger at the top and smaller at the bottom with a vapor inlet at the top and an outlet at the bottom, and a cooler having devaporizing and cooling elements and a casing larger at the bottom and smaller at the top with a vapor inlet at the bottom and an outlet at one end, said cooler casing being divided into a devaporizing chamber and an intercooler chamber, the cooler casing being removably connected against the side of the condenser, and the shell of the condenser forming one side of the cooler, with a water space between the condenser and the cooler, and connections for passing water through the condensing elements of the condenser.

and through the elements of the devaporizing chamber and intercooler chamber of the cooler.

4. A condensing unit comprising a surface condenser having a shell, a cooler having devaporizing and cooling elements, one side of the cooler being removably connected against the side of the condenser shell with provision for a water space between the condenser and cooler, an outer water head for the cooler, connections for supplying water to said head, a baffle in the head for guiding the water through the head to and through the devaporizing and cooling elements of the cooler, and connections for discharging the water from the water space between the surface condenser and the cooler.

5. A condensing unit comprising a surface condenser having a shell, a cooler divided transversely into devaporizer and inter-

cooler chambers, transversely extending devaporizing and cooling elements in said chambers respectively, one side of the cooler being removably connected against the side of the condenser shell, with provision for a water space between the condenser and the cooler, an outer water head for the cooler, connections for supplying water to the condenser and to said cooler head, a common inlet for said connections, a baffle in the cooler head for guiding the water through the head to and through the devaporizing and cooling elements of the cooler chambers respectively, and discharge connections for the condenser and for the water space between the condenser and the cooler.

In testimony whereof I have signed this specification.

PAUL A. BANCEL.
